FLASH LAMP STRUCTURE FOR CAMERAS

Filed Nov. 15, 1930

UNITED STATES PATENT OFFICE

HARRY H. HIPWELL, OF PITTSBURGH, PENNSYLVANIA

FLASH LAMP STRUCTURE FOR CAMERAS

Application filed November 15, 1930. Serial No. 495,883.

My invention relates to flash lamp structures for cameras, and more particularly to a structure for automatically effecting the ignition of a photographic flash lamp in timed relation with the actuation of a camera shutter.

In structures of this type, difficulty has been experienced in effecting proper synchronization or timing of the ignition of an illuminating flash to the operation of a camera shutter, particularly when shutters of the high speed type are employed.

One object of my invention is to provide a structure of the character referred to, with means for synchronizing the firing of a flash and the operation of a shutter.

Another object of my invention is to provide a flash lamp structure and a shutter-operating mechanism that is especially suitable for use in connection with high-speed camera shutters.

Still another object of my invention is to provide apparatus of the character referred to of generally simplified and improved form.

One form of structure embodying my invention is shown in the accompanying drawings, wherein Figure 1 is a face view of the apparatus, in operative connection with a camera; Fig. 2 is a plan view thereof, on an enlarged scale, with the lamp sockets and reflectors removed; Fig. 3 is a view, on an enlarged scale, taken on the line III-III of Fig. 1, and Fig. 4 is a fragmentary view of the apparatus of Fig. 3, with the plunger mechanism thereof latched in retracted position.

The structure is shown as embodying an ordinary dry cell battery casing 5, such as commonly employed in connection with small flash lamps. The casing will contain the necessary number of battery cells to produce the desired voltage. The casing 5 is provided with a cap 6 to which is suitably secured a bracket-like extension 7. The cap 6 constitutes a base for an ordinary lamp socket 8, as shown more particularly in Fig. 2, and into which a two-way plug 9 may be positioned, if desired. The sockets 9 carry flash lamps 10, such as are employed in photo-

graphic work, the lamps 10 each having a fusible element and being filled with a combustible gas and a flash powder or foil, so that combustion will be effected within the lamps when it is desired to produce illumination for photographic purposes, by closing the circuit through the lamps.

The lamps 10 are provided with reflectors 11 which are pivotally mounted on a lug 12 of the bracket-like extension 7, as shown more particularly in Fig. 2. The reflectors 11 may be moved back into folded position alongside of the battery casing 5, so that if the lamps 10 are removed, the structure is in compact form and can be easily carried in the pocket of a photographer, or may be readily packed for shipping. The lug 12 carries a threaded stud to which a thumb nut 13 is secured, so that the reflectors may be readily clamped thereby in set position.

A cylindrical casing 14 is carried by the bracket-like extension 7 and contains a piston 15 that is normally held in advanced position by means of a compression spring 16. The ends of the cylinder 14 are closed by end blocks 17 and 18, the upper end block 17 serving as an anvil for receiving the impacts of the piston 15.

The end block 17 is suitably secured in the forward end of the cylinder 14 and is provided with an opening 19 through which a stud or bushing 20 extends. The stud 20 is provided with an enlarged head portion and a clamp nut, and is insulated from the block 17 and the bracket 7, by means of insulating washers 21, and serves as a clamping member to secure the casing 14 to the extension 7. The stud 20 is of smaller diameter than the opening in the block 17, passageways 19a being provided in the head portion thereof to effect communication between the interior of the casing 14 and the opening 19. A nozzle 22 is threaded into the end block 17 and communicates with the opening 19.

A hose 23 is connected at one end to the nipple 22, the other end of the hose being connected to a pneumatic shutter actuator 24 that may be of any well-known type, such as employed in ordinary bulb-operated cameras. The member 24 actuates a shutter to expose

the film of a camera 25. Pressure for actuating the device 24 is secured by retracting the piston 15 against the contraction of the spring 16 and permitting the piston to be moved forwardly by the spring and thus create the desired air pressure in the cylinder 14, the compressed air discharging through the opening 19 and the nozzle 22.

For a purpose to be hereinafter described, 10 the initial movement of the piston 15 is ineffective to compress air in the cylinder 14. The cylinder 14 is provided with openings 32 intermediate its ends, the openings serving as exhaust ports to prevent the building up 15 of air pressure in the chamber until after the piston passes such openings.

The piston is drawn to retracted position by means of a handle 26 and is automatically latched in retracted position by means of a 20 radially movable trigger 27. The trigger 27 is carried by a spring 28 disposed circumferentially of the lower end of the casing 14, and is provided with a thumb piece 29a, by means of which the latch may be moved radially 25 outwardly. The trigger 27 normally bears against a shank 29 carried by the piston 15, such shank being provided with an undercut portion or notch 30 into which the trigger is projected by the spring 28, to maintain the 30 plunger in its retracted position. Upon movement of the trigger lever 27, the shank 29 will be released to allow the spring 16 to push the piston 15 forwardly.

It will be seen that during the initial 35 movement of the piston, no air pressure will be built up in the cylinder 14 until after the piston passes and closes the openings 32. During this portion of the movement of the plunger, the circuit for the lamps 10 will be 40 closed so that the lamps will be ignited in synchronism with, or in predetermined advanced relation to, the operation of the shutters.

A switch mechanism comprises a movable 45 contact member 33 and a stationary contact member 34. The movable contact member 33 is yieldably mounted within the piston shank 29, so that after the contacts are brought into engagement through movement 50 of the piston 15, they will be permitted to remain in contacting engagement during the remainder of the piston movement.

The movable contact member 33 is movable 55 longitudinally within the shank 29 and is prevented from falling out of the shank when the piston is retracted, by the peening over of the inner end of the shank at the point 33a, the contact being yieldably maintained in position at the inner end of the shank by 60 means of a spring 35.

The stationary contact member 34 which cooperates with the movable contact member 33 to control the circuit of the flash lamp is 65 extended through the bushing 20 and has threaded engagement therewith, so that the

contact may be relatively adjusted with respect to the contact 33. The contact 34 is normally extended into the cylinder such distance that its end is positioned adjacent to the openings 32, so that upon movement of the piston from its retracted position, the movable contact will engage the stationary contact during the initial movement of the piston, thereby completing the circuit to the lamps 10 before the piston covers the openings 32 and effects compression of air in the upper end of the cylinder.

In this manner, the contacts being relatively adjustable and normally caused to engage at a point lying within the portion of the casing where compression is eliminated by the release of air from the casing until the openings are closed by the piston, the lamps will be ignited at predetermined advanced timed relation with respect to the operation of the shutter by the further movement of the piston after closing the openings 32. Thus when high speed camera shutters are employed, the contacts will be adjusted to close the ignition circuit for the lamps previous to the operation of the shutter, thereby assuring that the flash will occur either in synchronism with the actuation of the shutter or in advanced timed relation therewith.

In order to control the point in the casing at which the piston will be effective to compress the air, a yieldable sleeve member 38 is slidably mounted exteriorly of the casing 14 and may be moved into position to cover the openings 32, or to cover such portions of said openings as is desired. In this manner, the point at which the air is initially compressed is determined by the position of the sleeve relative to the piston travel. The member 38 may be moved to completely cover the 105 openings 32 when the flash structure is not in use, to prevent dust and dirt from entering into the casing 14.

I claim as my invention:—

1. The combination with a camera shutter, 110 of an air compressor for actuating the same, comprising a piston movable in a cylinder, a switch for controlling a source of illumination, an operating connection between the piston and the switch, and exhaust means controlled by said piston for exhausting fluid from the compressor until after the said switch has been operated.

2. Flash lamp structure for cameras, comprising a battery casing and a flash lamp carried thereby, a compressor secured to the casing, and having a movable piston for compressing fluid therein, means for conducting fluid pressure from the compressor to a camera shutter, a switch for controlling the lamp and actuated by movement of the piston on its compression stroke, and exhaust means controlled by the said piston for preventing compression of fluid in the compressor during a portion of the stroke of the piston.

3. Flash lamp structure for cameras, comprising a battery casing and a flash lamp carried thereby, a compressor secured to the casing, and having a movable piston for compressing fluid therein, means for conducting fluid pressure from the compressor to a camera shutter, a switch for controlling the lamp and actuated by movement of the piston on its compression stroke, and exhaust means controlled by the said piston for preventing compression of fluid in the compressor during a portion of the stroke of the piston, the said switch being adjustably mounted in position to be actuated during the non-compressing portion of the stroke of the piston. 70
4. Flash lamp structure for cameras, comprising a cylinder and a piston movable therein, means for connecting the forward end of said cylinder to a camera shutter, means for moving said piston to compress fluid in the forward end of said cylinder, an exhaust passageway disposed intermediate the ends of the cylinder, and controlled by movement of said piston on its compression stroke, a switch for controlling a source of illumination, and a switch-operating member operated by said piston for actuating said switch during the initial movement of said piston. 80
5. Flash lamp structure for cameras, comprising a cylinder and a piston movable therein, means for connecting the forward end of said cylinder to a camera shutter, means for moving said piston to compress fluid in the forward end of said cylinder, an exhaust passageway disposed intermediate the ends of the cylinder and controlled by movement of said piston on its compression stroke, a switch for controlling a source of illumination, means for actuating said switch during the initial movement of said piston, and a yieldable sleeve member movable into position to cover a predetermined portion of said passageway. 85
6. Flash lamp structure for cameras, comprising a cylinder and a piston movable therein, means for connecting the forward end of said cylinder to a camera shutter, means for moving said piston to compress fluid in the forward end of said cylinder, an exhaust passageway disposed intermediate the ends of the cylinder, and controlled by movement of said piston on its compression stroke, a movable electric contact member carried by said piston, and a stationary contact member extending into the said cylinder to a point adjacent to said passageway, and in position to be engaged by the movable contact member during advance movement of the piston, the contact members serving to control a lamp circuit. 90
7. Flash lamp structure for cameras, comprising a cylinder and a piston movable therein, means for connecting the forward end of said cylinder to a camera shutter, means for moving said piston to compress fluid in the forward end of said cylinder, an exhaust passageway disposed intermediate the ends of the cylinder and controlled by movement of said piston on its compression stroke, a movable electric contact member carried by said piston, a stationary contact member extending into the said cylinder to a point adjacent to said passageway, and in position to be engaged by the movable contact member during advance movement of the piston, the contact members serving to control a lamp circuit, and the said stationary contact being adjustable relative to the point of closure of the passageway by the piston. 95
8. Flash lamp structure for cameras, comprising a cylinder and a piston movable therein, means for connecting the forward end of said cylinder to a camera shutter, means for moving said piston to compress fluid in the forward end of said cylinder, an exhaust passageway disposed intermediate the ends of the cylinder, and controlled by movement of said piston on its compression stroke, a switch for controlling a source of illumination, and a switch-operating member operated by said piston for actuating said switch during the initial movement of said piston, and a yieldable sleeve member movable into position to cover a predetermined portion of said passageway. 100
